UNITED STATES PATENT OFFICE.

ARTHUR SMITH D. FRENCH, OF BIXBY, OKLAHOMA.

PUMP-JACK.

1,335,960.

Specification of Letters Patent.

Patented Apr. 6, 1920.

Application filed June 3, 1919. Serial No. 301,394.

To all whom it may concern:

Be it known that I, ARTHUR S. D. FRENCH, a citizen of the United States, and a resident of Bixby, in the county of Tulsa and 5 State of Oklahoma, have invented certain new and useful Improvements in Pump-Jacks, of which the following is a specification.

My invention relates to pump jacks, and 10 more particularly to that type of pump jack including a normally stationary frame and a rocker mounted to oscillate thereon.

An important object of my invention is to provide a pump jack of this type with adjustable bearings whereby the pump jack 15 can be adapted to the varying conditions met with in different wells.

Another object is to provide adjustable 20 bearings whereby the stroke may be varied as desired.

Another object is to provide a pump jack with a rocker and adjustable bearings therefor and thereon; all of which are so constructed as to preserve strength and rigidity 25 and at the same time, allow of ready adjustment with the least manipulation.

Other objects and advantages reside in certain novel features of the construction, arrangement and combination of parts and 30 will become apparent as the description proceeds, reference being had to the accompanying drawings forming a part of this specification, and in which:

Figure 1 is a perspective view of the 35 pump jack assembled,

Fig. 2 is a detail perspective view of the rocker saddle,

Fig. 3 is a detail perspective view of the 40 adjustable hanger bearing,

Fig. 4 is a detail view showing in front elevation the clevis for the pull rods.

Referring to the drawings, it will be seen 45 my pump jack comprises a suitable base which may be in the form of a sill 10. A pair of forwardly inclined legs 11, preferably pipe sections, have their lower ends a substantial distance apart and seated in the sill 10, and have their upper ends open. These legs converge toward their upper ends 50 to form an inverted V, and together with the braces 12 constitute the normally stationary frame. Turn buckles 12' are provided in the braces 12 and comprise means whereby the position of the frame may be 55 varied.

An adjustable rocker bearing is mounted

on the legs 11 of the frame. This bearing comprises spaced journals 13 which consist of flattened body portions having aligned openings and integral stud pins 14 which project into the upper open ends of the pipe legs as shown in dotted lines in Fig. 1. A saddle block 15 has an integral depending lug 15' extending entirely across the bottom thereof, and this lug is provided with a transverse bore extending therethrough. The saddle block is mounted between the journals 13 and the bore thereof is aligned with the openings of the journals. A pivot bolt 16 is passed through the openings of the journals and the bore of the lug and is secured therein. The saddle block 15 is provided along its upper longitudinal edges with upstanding flanges 17 and a clamp member 18 is provided on each of its longitudinal edges with depending flanges 19. Bolts 20 coöperate with the saddle block and clamp member to effect the desired adjustment.

The rocker indicated generally at 21 is 80 mounted on the saddle block and secured thereto by the clamp 18 hereinbefore described. The rocker is triangularly shaped, having a horizontal arm, a downwardly depending arm at right angles to the horizontal arm, and an arm connecting the outer extremities of the horizontal arm and the downwardly depending arm. The rocker arms comprise spaced parallel bars 22 which overlap each other at the juncture of said 85 arms, as shown in Fig. 3. A sleeve 23 has its opening aligned with aligned openings provided in said overlapping portions and serves to maintain the bearings in proper spaced relation. A bolt 24 passes through the openings and through the sleeve, and firmly secures the whole.

The horizontal arm of the rocker is mounted upon the saddle block and the flanges thereof engage and confine the lower 100 portions of the parallel bars. Flanges of the clamp engage and confine the upper portions of the parallel bars and in this manner, the rocker is effectively secured in its adjusted position to the rocker bearing.

Adjacent the outer end of the horizontal arm of the rocker a hanger bearing 25 is adjustably secured. This hanger bearing comprises an upper bearing block 26 and a lower clamp member 27. The upper bearing block 110 and the lower clamp member are provided along their longitudinal edges with flanges

26' and 27' respectively, to engage the spaced parallel bars of the rocker arm and are held in firm engagement therewith by means of bolts 28. The bearing block 26 is provided 5 with a journal 29 and mounted on this journal is a hanger 30 in the form of an inverted U-bar. This hanger carries at its lower end the gripping clamp 31 which engages the polish-rod 32.

10 Adjacent the outer extremity of the downwardly depending arms of the rocker, the adjustable bearing 33 is secured. This bearing is provided with a clamp member and flanges, identical with that of the hanger bearing, for securing it to the rocker arm. The journal portion of this bearing carries 15 the cross head 34 to which the pull rods 35 are connected.

12 The outer ends of the pull rods are provided with a clevis 36 as shown in Fig. 4 for connection with the source of power. This clevis comprises a transverse pin 37 secured to the pull rods, and a hook 38 fastened to 25 said pin which is attached to the connections to the source of power.

13 In operation, the pull rod is connected to a source of power for imparting oscillatory movement to the rocker which in turn effects 30 a reciprocatory motion to the polish-rod of the pump.

14 Heretofore in the art requirements incident to the different conditions peculiar to various wells, have made it necessary to construct a special jack for each well, or at least 35 to tear down the jack and rebuild it to adapt it to these requirements. In my invention, any adjustment necessary to adapt the jack to the requirements in wells may be easily and quickly carried out. The position of the 40 frame may be adjusted by means of the turn-buckles, the rocker may be adjusted in the rocker bearings on said frame, the hanger bearing may be adjusted on the horizontal arm of the rocker, and the pull rod may be 45 adjusted on the depending arm of the rocker.

I claim:—

1. A pump jack comprising an adjustable frame including pipe legs open at their upper ends, journals provided with alined openings in their body portions and having 50 integral stud pins projecting into said open ends, a saddle block having a depending lug provided with a bore, said saddle block having the bore of its lug alined with said journal openings, a pivot bolt passing 55 through said journal openings and said saddle block bore and secured therein, a rocker mounted on said saddle block, and means associated with said saddle block for adjustably securing said rocker thereto.

2. A pump jack comprising an adjustable frame including pipe legs open at their upper ends, journals provided with alined openings in their body portions and having 60 integral stud pins projecting into said open ends, a rocker bearing oscillatably mounted between said journals, a rocker adjustably secured to said rocker bearing, and means 65 for oscillating said rocker.

3. A pump jack comprising a frame, a 70 rocker mounted for oscillating motion on said frame including spaced parallel bars having alined openings near each of their ends, spacing sleeves alined with said openings, and means extending through said sleeves for securing said bars in spaced relation, a rocker bearing mounted on said frame and upon which said rocker is mounted, a hanger bearing mounted on said rocker, and a pull rod bearing mounted on said rocker, 75 said rocker bearing, hanger bearing, and pull rod bearing including a block having flanges engageable with the outer face of said spaced parallel bars, a clamp member having flanges engageable with the outer 80 face of said parallel bar at the opposite edge thereof, and means coöperating with said clamp member and said block extending between said parallel bars.

ARTHUR SMITH D. FRENCH.
